UNITED STATES PATENT OFFICE

107,551

DESIGN FOR A COMBINED LAVATORY AND CABINET

George Sakier, New York, N. Y., assignor to The Accessories Company, Inc., New York, N. Y., a corporation of Delaware

Application November 13, 1936, Serial No. 65,884

Term of patent 14 years

To all whom it may concern:

Be it known that I, George Sakier, a citizen of the United States, residing at the city of New York, in the county and State of New York, have invented a new, original, and ornamental Design for a Combined Lavatory and Cabinet, of which the following is a specification, reference being had to the accompanying drawing, forming a part thereof.

In the drawing—

Figure 1 is a front elevation showing a combined lavatory and cabinet embodying my said design, and

Fig. 2 is an end elevation thereof.

I claim:

The ornamental design for a combined lavatory and cabinet, as shown.

GEORGE SAKIER.
